DESIGN FOR A SHOE

James J. Hickey, Binghamton, N. Y., assignor to Endicott Johnson Corporation, Endicott, N. Y., a corporation of New York

Application May 27, 1946, Serial No. 130,110

Term of patent 7 years

(Cl. D7—7)

To all whom it may concern:

Be it known that I, James J. Hickey, a citizen of the United States, residing at Binghamton, in the county of Broome and State of New York, have invented a new, original, and ornamental Design for a Shoe, of which the following is a specification, reference being had to the accompanying drawing, forming part thereof.

Referring to the drawing—

Fig. 1 is a side elevation of a shoe showing my new design;

Fig. 2 is a plan view thereof;

Fig. 3 is a section taken along line 3—3 of Fig. 1; and

Fig. 4 is a section taken along line 4—4 of Fig. 2.

The essential features of my design are shown in full lines.

I claim:

The ornamental design for a shoe, substantially as shown and described.

JAMES J. HICKEY.
